TERTIARY-AMINOALKYL 4-SUBSTITUTED-AMINO-2-ALKOXYTHIOLBENZOATES AND THEIR PREPARATION

Raymond O. Clinton, North Greenbush, and Stanley C. Laskowski, Menands, N. Y., assignors to Sterling Drug Inc., New York, N. Y., a corporation of Delaware

No Drawing. Application August 25, 1951,
Serial No. 243,738

20 Claims. (Cl. 260—293.4)

1

This invention relates to tertiary-aminoalkyl 4-substituted-amino-2-alkoxythiobenzoates and to their preparation.

The compounds have the general formula

where X is a lower alkylene radical having from two to four carbon atoms, NRR₁ is a tertiary-amino radical, R₂ is a lower alkyl radical having from one to six carbon atoms and R₃ is a lower alkyl radical having from one to six carbon atoms, inclusive, or a lower hydroxyalkyl radical having from two to six carbon atoms. These esters have valuable pharmacological properties, and in particular, local anesthetic activity.

In the above general formula, the lower alkylene radical designated as X has from two to four carbon atoms and has its two free valence bonds on different carbon atoms. Thus, X includes such examples as —CH₂CH₂—, —CH₂CH₂CH₂—,

—CH₂CH(CH₃), —CH₂CH₂CH₂CH₂—, —CH₂CH(CH₃)CH₂—, and the like.

The tertiary-amino radical shown above as NRR₁ comprehends dialkylamino radicals where R and R₁ are lower alkyl groups, alike or different, and each alkyl group having from one to six carbon atoms, such dialkylamino radicals including dimethylamino, diethylamino, ethylmethylamino, diisopropylamino, ethyl-n-propylamino, di-n-butylamino, di-n-hexylamino, and the like. Further, the tertiary-amino radical designated as NRR₁ encompasses saturated N-hetero-monocyclic radicals having from five to six ring atoms, illustrated by examples such as 1-piperidyl; (lower alkylated)-1-piperidyl such as 2-methyl-1-piperidyl, 3-ethyl-1-piperidyl, 4-methyl-1-piperidyl, 2,6-dimethyl-1-piperidyl; 1-pyrrolidyl; (lower alkylated)-1-pyrrolidyl such as 2-methyl-1-pyrrolidyl, 2,5-dimethyl-1-pyrrolidyl; 4-morpholinyl; and the like. In the above formula, R₂ when a lower alkyl radical having from one to six carbon atoms includes radicals such as methyl, ethyl, n-propyl, n-butyl, isobutyl, n-amyl, 2-amyl, n-hexyl, and the like. R₂ when representing a lower hydroxyalkyl radical having from two to six carbon atoms includes radicals such as 2-hydroxyethyl, 2-hydroxypropyl, 3-hydroxypropyl, 3-hydroxy-2-methylpropyl, 3-hydroxy-2,2-dimethylpropyl, 2-hydroxybutyl, 4-hydroxy-

2

butyl, 3-hydroxyamyl, 5-hydroxyamyl, 6-hydroxyhexyl, and the like.

The tertiary-aminoalkyl 4-substituted-amino-2-alkoxythiobenzoates of our invention can be prepared by various methods. The method preferred in practicing our invention comprises treating a tertiary-aminoalkyl 4-amino-2-alkoxythiobenzoate with a reducing agent in the presence of an alkanal or a hydroxyalcanal. This procedure is adaptable for the preparation of our compounds where R₂ is an alkyl or a hydroxyalkyl radical having from three to six carbon atoms, inclusive, the reactants being an alkanal or a hydroxy-alcanal, respectively, each having from three to six carbon atoms. Illustrative of this method of preparation is the formation of 2-diethylaminoethyl 4-n-propylamino-2-n-butoxythiobenzoate or 2-diethylaminoethyl 4-(3-hydroxypropyl)amino-2-n-butoxythiobenzoate by treating 2-diethylaminoethyl 4-amino-2-n-butoxythiobenzoate in the presence of propionaldehyde (propanal) or beta-hydroxypropionaldehyde (3-hydroxy-1-propanal), respectively, with a chemical reducing agent, such as zinc dust and acetic acid, iron and acetic acid, or with hydrogen in the presence of a sulfur-insensitive catalyst, e. g., molybdenum sulfide, cobalt sulfide.

The intermediate tertiary-aminoalkyl 4-amino-2-alkoxythiobenzoates, which are disclosed and claimed in our copending U. S. Patent application Serial No. 216,272, filed March 17, 1950, are conveniently prepared from 4-nitro-2-alkoxybenzoyl halides as shown in the following series of reactions where X, NRR₁ and R₂ have the meanings given hereinabove.

Thus, in step I a 4-nitro-2-alkoxybenzoyl halide (A) [preparation disclosed in our copending U. S. Patent applications Serial Nos. 168,843 and

168,844, each filed June 17, 1950] is treated with a tertiary-aminoalkanethiol (B) to yield a tertiary-aminoalkyl 4-nitro-2-alkoxythiobenzoate (C), which, in step II, is reduced to produce the corresponding tertiary-aminoalkyl 4-amino-2-alkoxythiobenzoate (D). A specific illustration of this series of reactions is the formation of 2-diethylaminoethyl 4-amino-2-n-butoxythiobenzoate by treating a 4-nitro-2-n-butoxybenzoyl halide, preferably the chloride, with 2-diethylaminoethanol to form 2-diethylaminoethyl 4-nitro-2-n-butoxythiobenzoate and reducing the nitro group of said thiol ester to form the corresponding 2-diethylaminoethyl 4-amino-2-n-butoxythiobenzoate.

Another style of synthesis of the thiol esters of our instant invention is the direct alkylation of a tertiary-aminoalkyl 4-amino-2-alkoxythiobenzoate with alkylating agents such as methyl iodide, ethyl bromide, n-propyl bromide, isobutyl iodide, 2-hydroxyethyl bromide, 4-hydroxybutyl chloride, and the like, in the presence of a hydrogen halide acceptor, e.g., sodium bicarbonate, potassium carbonate, etc. Thus, such treatment of 2-diethylaminoethyl 4-amino-2-n-butoxythiobenzoate with methyl iodide, ethyl bromide or 2-hydroxyethyl bromide yields 2-diethylaminoethyl 4-methylamino-2-n-butoxythiobenzoate, 2-diethylaminoethyl 4-ethylamino-2-n-butoxythiobenzoate or 2-diethylaminoethyl 4-(2-hydroxyethyl)amino-2-n-butoxythiobenzoate, respectively.

The tertiary-aminoalkyl 4-substituted-amino-2-alkoxythiobenzoates of our invention are therapeutically active whether employed in the form of their free bases or in the form of their salts with relatively non-toxic organic or inorganic acids. In practicing our invention we sometimes found it convenient to isolate our compounds in the form of their hydrochlorides. However, other acid addition salts are within the scope of our invention, such addition salts including the hydrobromides, sulfates, phosphates, citrates, sulfamates, tartrates, succinates, acetates, benzoates, oleates, and the like.

Specific embodiments of our invention are illustrated by the following examples.

EXAMPLE 1

(a) *Tertiary-aminoalkyl 4-nitro-2-alkoxythiobenzoates*

These substances were prepared by reacting a 4-nitro-2-alkoxybenzoyl halide, preferably the chloride, with a tertiary-aminoalkanethiol, as illustrated by the following preparation of 55 2-diethylaminoethyl 4-nitro-2-methoxythiobenzoate: 4-Nitro-2-methoxybenzoyl chloride

was prepared in quantitative yield by refluxing a mixture of 98.5 g. of 4-nitro-2-methoxybenzoic acid and 295 g. of thionyl chloride for two and one-half hours, evaporating in vacuo, adding 200 ml. of dry benzene and again evaporating in vacuo. To a cooled solution of 63.9 g. of 4-nitro-2-methoxybenzoyl chloride dissolved in 400 ml. of dry benzene was added slowly, with stirring, 39.5 g. of 2-diethylaminoethanol dissolved in 50 ml. of dry benzene, and the resulting reaction mixture was heated to boiling, cooled and diluted with dry benzene to a total volume of one liter. The tan colored product that separated on cooling was filtered and recrystallized, with decolorization using activated carbon, from absolute ethanol-petroleum ether, thereby yielding the desired product, 2-diethylaminoethyl 4-nitro-2-methoxythiobenzoate in the form of its hydrochloride. After being dried at 70° C. in vacuo, it melted at 146.4-147.9° C. (cor.).

In the preparation of the acid chlorides where the 2-alkoxy substituent is higher in carbon content than ethoxy (e.g., 4-nitro-2-n-butoxybenzoyl chloride), the reaction is preferably run 25 in the presence of pyridine as a hydrogen chloride acceptor to minimize cleavage of the alkoxy group. This procedure is illustrated as follows: To 1 mole of acid, e.g., 4-nitro-2-n-butoxybenzoic acid, and 1.2 moles of pure pyridine in 4 volumes of dry benzene was added 1.0 mole of thionyl chloride at 25° C., the mixture refluxed for about twenty minutes, cooled in ice, treated with stirring with 1.0 mole of the tertiary-aminoalkanethiol, e.g., 3-(1-piperidyl)propane thiol, and the reaction mixture mixed well. The solvent was removed in vacuo and the residue dissolved in water. Excess ammonium hydroxide was added and the mixture extracted with toluene. The toluene solution was dried and the solvent removed in vacuo. More toluene was added and again evaporated in vacuo (this procedure was to remove pyridine), thereby leaving the pure base, e.g., 3-(1-piperidyl)propyl 4-nitro-2-n-butoxythiobenzoate.

Additional tertiary-aminoalkyl 4-nitro-2-alkoxybenzoates, in the form of their hydrochlorides, prepared according to the above described procedures from the appropriate 4-nitro-2-alkoxybenzoyl chloride and tertiary-amino-alkanethiol are given in Table I.

TABLE I

R ₂	X	NRR ₁	Hydrochloride, M. P./°C. (cor.)
CH ₃	CH ₂ CH ₂ CH ₃	1-piperidyl	200.0-201.1 ¹
CH ₃	CH ₂ CH ₂ CH ₂	N(C ₂ H ₅) ₂	137.0-158.0
CH ₃	CH ₂ CH ₂ CH ₂ CH ₂	N(C ₂ H ₅) ₂	109.0-110.6
CH ₂ CH ₃	CH ₂ CH ₂ CH ₂	N(C ₂ H ₅) ₂	117.2-118.8
CH ₂ CH ₃	CH ₂ CH ₂	N(C ₂ H ₅) ₂	185.0-185.8
CH ₂ CH ₃	CH ₂ CH ₂	1-piperidyl	185.9-187.7 ²
CH ₂ CH ₃	CH ₂ CH ₂ CH ₂	1-piperidyl	106.6-108.0
CH ₂ CH ₃	CH ₂ CH ₂ CH ₂	2-CH ₃ -1-piperidyl	210.0-211.5
CH ₂ CH ₃	CH ₂ CH ₂	N(C ₂ H ₅) ₂	171.7-173.3

CH ₂ CH ₂ CH ₂ CH ₃	CH ₂ CH ₂ CH ₂	1-piperidyl	170.0-171.0
CH ₂ CH ₂ CH ₂ CH ₃	CH ₂ CH ₂	2-CH ₃ -1-piperidyl	165.0-165.9
CH ₂ CH ₂ CH ₂	CH ₂ CH ₂	N(C ₂ H ₅) ₂	163.4-194.6
CH ₂ CH ₂ CH ₂ CH ₂ CH ₂ CH ₃	CH ₂ CH ₂	N(C ₂ H ₅) ₂	115.4-116.6

¹ Thiol ester base melts at 60.1-61.2° C. (cor.).² Thiol ester base melts at 65.6-67.7° C. (cor.).³ Thiol ester base melts at 55.3-57.2° C. (cor.).

Additional tertiary-aminoalkyl 4-nitro-2-alkoxythiobenzoates which can be prepared according to the foregoing procedure using the appropriate 4-nitro-2-alkoxybenzoyl chloride and tertiary-aminoalkanethiol include the following: 2-diethylaminoethyl 4-nitro-2-ethoxythiobenzoate; 3-(1-pyrrolidyl)propyl 4-nitro-2-n-propoxythiobenzoate; 2-(2,5-dimethyl-1-pyrrolidyl)-ethyl 4-nitro-2-n-hexoxythiobenzoate; 4-dimethylaminobutyl 4-nitro-2-n-butoxythiobenzoate; 2-(di-n-butyldiamino)ethyl 4-nitro-2-isoaminoxythiobenzoate; 2-(3-ethyl-1-piperidyl)ethyl 4-nitro-2-isobutoxythiobenzoate; 3-(2-methyl-1-pyrrolidyl)propyl 4-nitro-2-(3-aminoxythiobenzoate; 3-dimethylamino-2-propyl 4-nitro-2-n-butoxythiobenzoate; 2-(4-morpholinyl)ethyl 4-nitro-2-n-aminoxythiobenzoate; 2-(2-methyl-1-piperidyl)ethyl 4-nitro-2-ethoxythiobenzoate; and 3-diethylaminopropyl 4-nitro-2-n-hexoxythiobenzoate.

(b) *2-diethylaminoethyl 4-amino-2-methoxythiobenzoate*

To a hot stirred mixture of 75.0 g. of powdered iron (ferrum reductum), 1 ml. of concentrated hydrochloric acid and 600 ml. of 50% ethanol was added slowly 78.0 g. of 2-diethylaminoethyl 4-nitro-2-methoxythiobenzoate hydrochloride over a period of about ten minutes. The resultant solution was heated with stirring for another twenty minutes, after which time an excess (about 35 g.) of sodium bicarbonate was added. The mixture was warmed and stirred for an additional twenty minutes, filtered through a filter aid and the insoluble material was washed well with hot absolute ethanol. The combined filtrates and washings were concentrated by distilling in vacuo, and the residue was cooled and extracted with ethyl acetate. The combined extracts were dried over anhydrous potassium carbonate or anhydrous calcium sulfate and the solvent removed by distilling in vacuo. The oily residue, which crystallized when cooled and triturated with a glass rod, was recrystallized, with decolorization using activated carbon, from ethyl acetate-n-hexane and dried in vacuo at 56° C., thereby yielding the product, 2-diethylaminoethyl 4-amino-2-methoxythiobenzoate, in the form of the free base, M. P. 77.0-78.0° C. (cor.).

Anal.—Calcd. for $C_{14}H_{22}N_2O_2S$: N, 9.92. Found: N, 9.75.

The phosphate salt of this thiol ester was prepared by treating a solution of 2-diethylaminoethyl 4-amino-2-methoxythiobenzoate in free base form in a suitable solvent, such as ethyl acetate, with an equivalent amount of 85% phosphoric acid, filtering the precipitated phosphate and recrystallizing the same from dilute ethanol. The resultant salt, 2-diethylaminoethyl 4-amino-2-methoxythiobenzoate phosphate, melted at 188.2-190° C. (cor.) when dried at 100° C. in vacuo.

Anal.—Calcd. for $C_{14}H_{22}N_2O_2S \cdot H_3PO_4$: S, 8.42; N, 7.36; C, 44.19; H, 6.58. Found: S, 8.60; N, 7.35; C, 44.19; H, 6.44.

The dihydrochloride addition salt of this thiol ester can be prepared by dissolving a portion of said ester in free base form in a suitable solvent, such as ethyl acetate, and treating the solution with an excess of anhydrous ether containing 20% by weight of anhydrous hydrogen chloride. The gummy precipitate is separated from the supernatant liquid by decanting and is triturated with ethyl acetate. Again the ethyl acetate is decanted and the crude precipitate is recrystall-

ized from absolute ethanol, absolute ethanol-ether or absolute ethanol-ethyl acetate and dried at 60° C in vacuo. Thus obtained is 2-diethylaminoethyl 4-amino-2-methoxythiobenzoate dihydrochloride.

The monohydrochloride salt of this thiol ester is prepared by dissolving the ester in free base form in a suitable solvent, such as ethyl acetate, treating the solution with an excess of anhydrous ether containing 20% by weight of anhydrous hydrogen chloride, triturating the gummy precipitate with ethyl acetate, as above, and dissolving the resulting crude dihydrochloride in a minimum quantity of hot absolute ethanol and to the solution is added a slight excess of the purified ester in free base form dissolved in a minimum quantity of hot absolute ethanol. The crystalline precipitate which separates on cooling is collected and washed with ethyl acetate. To ensure more complete precipitation, ethyl acetate can be added to the cooled mixture before filtering. Recrystallization of the precipitate from absolute ethanol or absolute ethanol-ethyl acetate yields, in purified form, 2-diethylaminoethyl 4-amino-2-methoxythiobenzoate monohydrochloride.

Other tertiary-aminoalkyl 4-amino-2-alkoxythiobenzoates can be prepared according to the foregoing procedure using the corresponding tertiary-aminoalkyl 4-nitro-2-alkoxythiobenzoate hydrochloride in place of 2-diethylaminoethyl 4-nitro-2-methoxythiobenzoate hydrochloride. Thus, 2-diethylaminoethyl 4-amino-2-ethoxythiobenzoate, 3-(1-pyrrolidyl)propyl 4-amino-2-n-propoxythiobenzoate, 2-(2,5-dimethyl-1-pyrrolidyl)ethyl 4-amino-2-n-hexoxythiobenzoate, 4-dimethylaminobutyl 4-amino-2-n-butoxythiobenzoate, 2-(di-n-butyldiamino)ethyl 4-amino-2-isoaminoxythiobenzoate, 2-(3-ethyl-1-piperidyl)-ethyl 4-amino-2-isobutoxythiobenzoate, 3-(2-methyl-1-pyrrolidyl)-propyl 4-amino-2-(3-aminoxythiobenzoate, 3-dimethylamino-2-propyl 4-amino-2-n-butoxythiobenzoate, 2-(4-morpholinyl)ethyl 4-amino-amino-2-n-aminoxythiobenzoate, 2-(2-methyl-1-piperidyl)ethyl 4-amino-2-ethoxythiobenzoate and 3-diethylamino-propyl 4-amino-2-n-hexoxythiobenzoate are obtained, respectively, from the hydrochlorides of 2-diethylaminoethyl 4-nitro-2-ethoxythiobenzoate, 3-(1-pyrrolidyl)propyl 4-nitro-2-n-propoxythiobenzoate, 2-(2,5-dimethyl-1-pyrrolidyl)ethyl 4-nitro-2-n-hexoxythiobenzoate, 4-dimethylaminobutyl 4-nitro-2-n-butoxythiobenzoate, 2-(di-n-butyldiamino)ethyl 4-nitro-2-isoaminoxythiobenzoate, 2-(3-ethyl-1-piperidyl)-ethyl 4-nitro-2-isobutoxythiobenzoate, 3-(2-methyl-1-pyrrolidyl)propyl 4-nitro-2-(3-aminoxythiobenzoate, 3-dimethylamino-2-propyl 4-nitro-2-n-butoxythiobenzoate, 2-(4-morpholinyl)ethyl 4-nitro-2-n-aminoxythiobenzoate, 2-(2-methyl-1-piperidyl)ethyl 4-nitro-2-ethoxythiobenzoate and 3-diethylaminopropyl 4-nitro-2-n-hexoxythiobenzoate. Alternatively, the foregoing reactions can be run using said tertiary-aminoalkyl 4-nitro-2-alkoxythiobenzoates in form of their free bases.

(c) *2-diethylaminoethyl 4-n-amylamino-2-methoxythiobenzoate*

To a warm stirred mixture of 13.0 g. of 2-diethylaminoethyl 4-amino-2-methoxythiobenzoate, 12.1 g. of zinc dust, 11.4 g. of glacial acetic acid and 200 ml. of dry benzene was added 4.81 g. of n-valeraldehyde (1-pentanal) in 25 ml. of dry benzene over a period of about fifteen min.

utes. The resulting mixture was refluxed with stirring for one hour. Another 1 ml. portion of n-valeraldehyde was added and refluxing continued for another thirty minutes. The hot reaction mixture was filtered, and the filtrate was cooled and made basic to litmus with concentrated ammonium hydroxide. The product that separated was extracted with benzene. During this particular extraction it was necessary to filter the extraction mixture through a filter-aid in order to break up an emulsion. The benzene extract was then dried over anhydrous potassium carbonate. Removal of the benzene in vacuo yielded, as a viscous, golden brown oil, an excellent yield of 2-diethylaminoethyl 4-n-amylamino-2-methoxythiobenzoate.

This product was converted into its hydrochloride addition salt as follows: The basic ester was dissolved in ethyl acetate and the resulting solution was treated with ethereal-hydrogen chloride (20% by weight of HCl) with cooling, whereupon the dihydrochloride separated as a gummy material. The supernatant liquid was decanted and the gum was dissolved in a minimum quantity of hot absolute ethanol, 1-2 ml. of ethereal-hydrogen chloride was added, the resulting solution cooled and ethyl acetate was added to turbidity. The resulting white crystalline product, 2-diethylaminoethyl 4-n-amylamino-2-methoxythiobenzoate dihydrochloride, melted at 149.2-150.5° C. (cor.) when recrystallized twice from absolute ethanol-ethyl acetate, containing 1-2 ml. of ethereal-hydrogen chloride.

Anal.—Calcd. for $C_{15}H_{32}N_2O_2S \cdot 2HCl$: C, 53.89; H, 8.09; S, 7.57. Found: C, 53.82; H, 7.89; S, 7.44.

Following the above procedure but using n-caproaldehyde (1-hexanal) in place of n-valeraldehyde there is obtained 2-diethylaminoethyl 4-n-hexylamino-2-methoxythiobenzoate.

Other tertiary-aminoalkyl 4-n-amylamino-2-alkoxythiobenzoates which can be prepared according to the foregoing procedure using the appropriate tertiary-aminoalkyl 4-amino-2-alkoxythiobenzoate in place of 2-diethylaminoethyl 4-amino-2-methoxythiobenzoate include the following: 2-diethylaminoethyl 4-n-amylamino-2-ethoxythiobenzoate; 3-(1-pyrrolidyl)-propyl 4-n-amylamino-2-n-propoxythiobenzoate; 4-diethylaminobutyl 4-n-amylamino-2-n-butoxythiobenzoate; 2-(di-n-butylamino)ethyl 4-n-amylamino-2-isoamylaminothiobenzoate; and 2-(2-methyl-1-piperidyl)ethyl 4-n-amylamino-2-ethoxythiobenzoate.

EXAMPLE 2

(a) 3-diethylaminopropyl 4-amino-2-methoxythiobenzoate

When the procedure described above for Example 1b was followed but using 22.8 of powdered iron, 1 ml. of concentrated hydrochloric acid, 400 ml. of dilute ethanol (about 65%) and 24.6 g. of 3-diethylaminopropyl 4-nitro-2-methoxythiobenzoate hydrochloride, there was obtained a quantitative yield of 3-diethylaminopropyl 4-amino-2-methoxythiobenzoate. This thiol ester, in the form of its phosphate salt, melted at 208.0-208.9° C. (cor.).

Anal.—Calcd. for $C_{15}H_{32}N_2O_2S \cdot H_3PO_4$: S, 8.12; H_3PO_4 , 24.85. Found: S, 8.24; H_3PO_4 , 25.02.

(b) 3-diethylaminopropyl 4-n-butylamino-2-methoxythiobenzoate

To a warm stirred mixture of 12.5 g. of 3-diethylaminopropyl 4-amino-2-methoxythiobenzoate, 11.0 g. of zinc dust, 10.3 g. of glacial acetic

acid and 200 ml. of dry benzene was added 3.67 g. of n-butyraldehyde (1-butanal) in 50 ml. of dry benzene over a period of about fifteen minutes. The resulting mixture was refluxed with stirring for one hour. Another 1 ml. portion of n-butyraldehyde was added and refluxing continued for an additional thirty minutes. The hot reaction mixture was filtered; the filtrate was cooled and made basic to litmus with concentrated ammonium hydroxide. The oil that separated was taken up with dry benzene. The benzene extract was dried over anhydrous potassium carbonate. The benzene was then removed by distilling in vacuo to yield 13 g. of 3-diethylaminopropyl 4-n-butylamino-2-methoxythiobenzoate, an amber, viscous oil.

This basic ester was purified by converting it to its dihydrochloride acid addition salt and regenerating the basic ester therefrom as follows: The basic ester was dissolved in ethyl acetate. The resulting solution was washed well with water, treated with ethereal-hydrogen chloride and cooled. The acid addition salt was extracted with water and the aqueous extract was washed with ether, decolorized with decolorizing charcoal, and made basic to litmus with concentrated ammonium hydroxide. The liberated base was taken up with ethyl acetate and the ethyl acetate solution was dried over anhydrous potassium carbonate. The ethyl acetate was removed by distilling in vacuo and the resultant oil was dissolved in absolute ether. After the ethereal solution had been charcoalized, the ether was evaporated in vacuo, thereby yielding the product as an amber, viscous oil which was then dried at 0.03 mm. pressure of Hg for four hours.

Anal.—Calcd. for $C_{19}H_{32}N_2O_2S$: S, 9.09; N, 7.94. Found: S, 8.91; N, 7.70.

Alternatively, the above compound can be prepared by direct alkylation of 3-diethylaminopropyl 4-amino-2-methoxythiobenzoate with n-butyl bromide. Similarly, using methyl iodide, ethyl chloride or 2-hydroxyethyl bromide in place of n-butyl bromide, there is obtained, respectively, 3-diethylaminopropyl 4-methylamino-2-methoxythiobenzoate, 3-diethylaminopropyl-4-ethylamino-2-methoxythiobenzoate or 3-diethylaminopropyl 4-(2-hydroxyethyl)amino-2-methoxythiobenzoate.

Other tertiary-aminoalkyl 4-n-butylamino-2-alkoxythiobenzoates which can be prepared according to the foregoing procedure using the appropriate tertiary-aminoalkyl 2-alkoxythiobenzoate in place of 3-diethylaminopropyl 4-amino-2-methoxythiobenzoate include the following: 2-(2,5-dimethyl-1-pyrrolidyl)ethyl 4-n-butylamino-2-n-hexoxythiobenzoate; 2-(3-ethyl-1-piperidyl)ethyl 4-n-butylamino-2-isobutoxythiobenzoate; 3-(2-methyl-1-pyrrolidyl)propyl 4-n-butylamino-2-(3-amino)thiobenzoate; 3-dimethylamino-2-propyl 4-n-butylamino-2-n-butoxythiobenzoate; 2-(4-morpholinyl)ethyl 4-n-butylamino-2-n-aminothiobenzoate; and 3-diethylaminopropyl 4-n-butylamino-2-n-hexoxythiobenzoate.

EXAMPLE 3

(a) 3-(1-piperidyl)propyl 4-amino-2-methoxythiobenzoate

This preparation was carried out according to the procedure described above for Example 1b using the following reactants: 19.7 g. of powdered iron, 1 ml. of concentrated hydrochloric acid, 400 ml. of 50% ethanol and 22.0 g. of 3-(1-piper-

idyl) propyl 4-nitro-2-methoxythiolbenzoate hydrochloride. There was thus obtained a quantitative yield of 3-(1-piperidyl) propyl 4-amino-2-methoxythiolbenzoate, which in the form of its phosphoric acid addition salt melted at 202.5-203.4° C. (cor.).

Anal.—Calcd. for $C_{16}H_{24}N_2O_2S \cdot H_3PO_4$: S, 7.88; H_3PO_4 , 24.12. Found: S, 7.94; H_3PO_4 , 24.20.

(b) 3-(1-piperidyl) propyl 4-n-butylamino-2-methoxythiolbenzoate

This preparation was carried out according to the procedure described above for Example 2b but using the following reactants: 12.0 g. of 3-(1-piperidyl) propyl 4-amino-2-methoxythiolbenzoate, 10.2 g. of zinc dust, 9.6 g. of glacial acetic acid, 200 ml. of dry benzene and 3.4 g. of n-butyraldehyde in 50 ml. of dry benzene. There was thus obtained a quantitative yield of 3-(1-piperidyl) propyl 4-n-butylamino-2-methoxythiolbenzoate, a straw colored oil.

Anal.—Calcd. for $C_{20}H_{32}N_2O_2S$: N, 7.68; S, 8.79. Found: N, 7.94; S, 8.73.

EXAMPLE 4

(a) 4-diethylaminobutyl 4-amino-2-methoxythiolbenzoate

When the procedure described above for Example 1b was followed but using 37.8 g. of powdered iron, 1 ml. of concentrated hydrochloric acid, 400 ml. of 50% ethanol and 42.5 g. of 4-diethylaminobutyl 4-nitro-2-methoxythiolbenzoate hydrochloride, there was obtained 31 g. of 4-diethylaminobutyl 4-amino-2-methoxythiolbenzoate. This thiol ester, in the form of its phosphoric acid addition salt, melted at 198.1-199.1° C. (cor.).

Anal.—Calcd. for $C_{16}H_{24}N_2O_2S \cdot H_3PO_4$: S, 7.85; H_3PO_4 , 24.00. Found: S, 7.85; H_3PO_4 , 24.29.

(b) 4-diethylaminobutyl 4-n-butylamino-2-methoxythiolbenzoate

When the procedure described above for Example 2b was followed using 21 g. of 4-diethylaminobutyl 4-amino-2-methoxythiolbenzoate, 17.7 g. of zinc dust, 16.7 g. of glacial acetic acid, 300 ml. of dry benzene and 5.9 g. of n-butyraldehyde in 50 ml. of dry benzene, there was obtained 4-diethylaminobutyl 4-n-butylamino-2-methoxythiolbenzoate, an amber colored oil.

Anal.—Calcd. for $C_{20}H_{34}N_2O_2S$: N, 7.64; S, 8.74. Found: N, 7.49; S, 8.56.

EXAMPLE 5

(a) 2-diethylaminoethyl 4-amino-2-n-butoxythiolbenzoate

This thiol ester was formed when the procedure described above for Example 1b was followed but using 47.4 g. of powdered iron, 1 ml. of concentrated hydrochloric acid, 500 ml. of 50% ethanol and 50.0 g. of 2-diethylaminoethyl 4-nitro-2-n-butoxythiolbenzoate. There was thus obtained 42 g. of 2-diethylaminoethyl 4-amino-2-n-butoxythiolbenzoate, which in the form of its monohydrochloride salt melted at 155.0-155.5° C. (cor.) when recrystallized, with decolorization using activated carbon, from absolute ethanol-n-pentane.

Anal.—Calcd. for $C_{17}H_{28}N_2O_2S \cdot HCl$: N, 7.76; Cl, 9.82. Found: N, 7.63; Cl, 9.55.

(b) 2-diethylaminoethyl 4-n-butylamino-2-n-butoxythiolbenzoate

When the procedure described above for Example 2b is followed but using 2-diethylamino-

ethyl 4-amino-2-n-butoxythiolbenzoate in place of 3-diethylaminopropyl 4-amino-2-methoxythiolbenzoate the resulting product is 2-diethylaminoethyl 4-n-butylamino-2-n-butoxythiolbenzoate.

EXAMPLE 6

(a) 2-diethylaminoethyl 4-amino-2-n-propoxythiolbenzoate

When the procedure described above for Example 1b was followed but using 62.5 g. of powdered iron, 1 ml. of concentrated hydrochloric acid, 500 ml. of 50% ethanol and 64.0 g. of 2-diethylaminoethyl 4-nitro-2-n-propoxythiolbenzoate, there are obtained 40.0 g. of 2-diethylaminoethyl 4-amino-2-n-propoxythiolbenzoate. This thiol ester, in the form of its phosphate salt, melted at 150.4-151.8° C. (cor.).

Anal.—Calcd. for $C_{16}H_{26}N_2O_2S \cdot H_3PO_4$: N, 6.85; H_3PO_4 , 24.00. Found: N, 6.72; H_3PO_4 , 23.98.

(b) 2-diethylaminoethyl 4-n-butylamino-2-n-propoxythiolbenzoates

To a warm stirred mixture of 16.0 g. of 2-diethylaminoethyl 4-amino-2-n-propoxythiolbenzoate, 13.5 g. of zinc dust, 12.7 g. of glacial acetic acid and 200 ml. of dry benzene was added 4.5 g. of n-butyraldehyde in 50 ml. of dry benzene over a period of fifteen minutes. The resulting mixture was refluxed with stirring for one hour. Another 1 ml. portion of n-butyraldehyde was added and refluxing continued for an additional thirty minutes. The hot reaction mixture was filtered, and the filtrate was cooled and made basic to litmus with concentrated ammonium hydroxide. The product that separated was extracted with benzene (or ethyl acetate). The benzene extract was washed with water and dried over anhydrous calcium sulfate. Concentration of the dried benzene solution in vacuo yielded, as an amber, viscous oil, the theoretical amount of 2-diethylaminoethyl 4-n-butylamino-2-n-propoxythiolbenzoate.

This basic ester was converted into its dihydrochloride as follows: 5 g. of the ester was dissolved in ethyl acetate and to this solution was added an excess of ethereal-hydrogen chloride solution (20% by weight of HCl) whereupon the dihydrochloride separated as a gummy material. The mixture was diluted with absolute ether (to a total volume of about 500 ml.) and the supernatant liquid was decanted from the gummy precipitate. The precipitate was triturated three times with warm ethyl acetate and was then dissolved in a minimum amount of hot absolute ethanol, and to the resulting solution was added about 1 ml. of said ethereal-hydrogen chloride solution. The resulting solution was decolorized with decolorizing charcoal, cooled and treated with another one ml. portion of ethereal-hydrogen chloride solution and a small amount of dry acetone, whereupon there separated, as a finely divided pale yellow material, 2-diethylaminoethyl 4-n-butylamino-2-n-propoxythiolbenzoate dihydrochloride, which when recrystallized another time from absolute ethanol-acetone (dry) melted at 142.2-143.9° C. (cor.).

Anal.—Calcd. for $C_{20}H_{34}N_2O_2S \cdot 2HCl$: Cl, 16.13; S, 7.29. Found: Cl, 16.08; S, 7.16.

EXAMPLE 7

(a) 2-(1-piperidyl)ethyl 4-amino-2-n-propoxythiolbenzoate

This thiol ester was prepared according to the procedure described above for Example 1b but

11

using the following reactants: 26.5 g. of powdered iron, 1 ml. of concentrated hydrochloric acid, 350 ml. of 50% ethanol and 28.0 g. of 2-(1-piperidyl)-ethyl 4-nitro-2-n-butoxythiobenzoate. The yield of the 4-amino thiol ester was 24 g. This ester in the form of its monohydrochloride addition salt melted at 189.2-190.9° C. (cor.).

Anal.—Calcd. for $C_{17}H_{26}N_2O_2S \cdot HCl$: N, 7.80; Cl, 9.87; S, 8.93. Found: N, 7.54; Cl, 9.72; S, 9.05.

(b) 2-(1-piperidyl)ethyl 4-n-butylamino-2-n-butoxythiobenzoate

Following the procedure described hereinabove for Example 2b but using 2-(1-piperidyl)ethyl 4-amino-2-n-butoxythiobenzoate in place of 3-diethylaminopropyl 4-amino-2-methoxythiobenzoate there is obtained 2-(1-piperidyl)ethyl 4-n-butylamino-2-n-butoxythiobenzoate.

EXAMPLE 8

(a) 3-diethylaminopropyl 4-amino-2-ethoxythiobenzoate

When the procedure described above for Example 1b was followed but using 35.3 g. of powdered iron, 1 ml. of concentrated hydrochloric acid, 400 ml. of dilute ethanol and 35.8 g. of 3-diethylaminopropyl 4-nitro-2-ethoxythiobenzoate, there was obtained 30.8 g. of 3-diethylaminopropyl 4-amino-2-ethoxybenzoate. This thiol ester, in the form of its monohydrochloride salt, melted at 175.0-176.3° C. (cor.).

Anal.—Calcd. for $C_{16}H_{28}N_2O_2S \cdot HCl$: N, 8.07; Cl, 10.22. Found: N, 7.83; Cl, 10.40.

(b) 3-diethylaminopropyl 4-n-hexylamino-2-ethoxythiobenzoate

When the procedure described above for Example 2b is followed but using 3-diethylaminopropyl 4-amino-2-ethoxythiobenzoate and caproaldehyde (1-hexanal) in place of 3-diethylaminopropyl 4-amino-2-methoxythiobenzoate and n-butylaldehyde, respectively, the resulting product is 3-diethylaminopropyl 4-n-hexylamino-2-ethoxythiobenzoate.

EXAMPLE 9

(a) 2-(1-piperidyl)ethyl 4-amino-2-n-butoxythiobenzoate

When the procedure described above for Example 1b was followed but using 27.1 g. of powdered iron, 1 ml. of concentrated hydrochloric acid, 350 ml. of dilute ethanol and 29.5 g. of 2-(1-piperidyl)ethyl 4-nitro-2-n-butoxythiobenzoate, there was obtained about 27 g. of 2-(1-piperidyl)-ethyl 4-amino-2-n-butoxythiobenzoate. This thiol ester, in the form of its monohydrochloride salt, melted at 172.3-173.9° C. (cor.).

Anal.—Calcd. for $C_{18}H_{28}N_2O_2S \cdot HCl$: N, 7.51; Cl, 9.50. Found: N, 7.38; Cl, 9.38.

(b) 2-(1-piperidyl)ethyl 4-n-butylamino-2-n-butoxythiobenzoate

When the procedure described above for Example 2b is followed but substituting 2-(1-piperidyl)ethyl 4-amino-2-n-butoxythiobenzoate for 3-diethylaminopropyl 4-amino-2-methoxythiobenzoate, the resulting ester is 2-(1-piperidyl)ethyl 4-n-butylamino-2-n-butoxythiobenzoate.

EXAMPLE 10

(a) 2-(2-methyl-1-piperidyl)ethyl 4-amino-2-n-butoxythiobenzoate

This preparation was carried out according to the procedure described above for Example 1b

12

but using 31.4 g. of powdered iron, 1 ml. of concentrated hydrochloric acid, 400 ml. of dilute ethanol and 35.6 g. of 2-(2-methyl-1-piperidyl)-ethyl 4-nitro-2-n-butoxythiobenzoate. The product thus obtained was 2-(2-methyl-1-piperidyl)ethyl 4-amino-2-n-butoxythiobenzoate (30 g.), which in the form of its hydrochloride salt melted at 191.2-192.3° C. (cor.).

Anal.—Calcd. for $C_{10}H_{30}N_2O_2S \cdot HCl$: N, 7.24; Cl, 9.16. Found: N, 7.28; Cl, 9.02.

(b) 2-(2-methyl-1-piperidyl)ethyl 4-n-butylamino-2-n-butoxythiobenzoate

When the procedure described above for Example 2b is followed but using 2-(2-methyl-1-piperidyl)ethyl 4-amino-2-n-butoxythiobenzoate instead of 3-diethylaminopropyl 4-amino-2-methoxythiobenzoate, there is obtained 2-(2-methyl-1-piperidyl)ethyl 4-n-butylamino-2-n-butoxythiobenzoate.

EXAMPLE 11

(a) 2-(2-methyl-1-piperidyl)ethyl 4-amino-2-n-propoxythiobenzoate

When the procedure described above for Example 1b was followed but using 32.6 g. of powdered iron, 1 ml. of concentrated hydrochloric acid, 400 ml. of dilute ethanol and 35.5 g. of 2-(2-methyl-1-piperidyl)ethyl 4-nitro-2-n-propoxythiobenzoate, there was obtained 21.5 g. of 2-(2-methyl-1-piperidyl)ethyl 4-amino-2-n-propoxythiobenzoate. This thiol ester, in the form of its dihydrochloride salt, melted at 175-180° C. (cor.) and did not melt up to 300° C.

Anal.—Calcd. for $C_{18}H_{28}N_2O_2S \cdot 2HCl$: N, 6.84; Cl, 17.32. Found: N, 7.11; Cl, 17.61.

(b) 2-(2-methyl-1-piperidyl)ethyl 4-n-butylamino-2-n-propoxythiobenzoate

Following the procedure described above for Example 2b but using 2-(2-methyl-1-piperidyl)-ethyl 4-amino-2-n-propoxythiobenzoate instead of 3-diethylaminopropyl 4-amino-2-methoxythiobenzoate, there is obtained 2-(2-methyl-1-piperidyl)ethyl 4-n-butylamino-2-n-propoxythiobenzoate.

EXAMPLE 12

(a) 3-(1-piperidyl)propyl 4-amino-2-n-propoxythiobenzoate

When the procedure described above for Example 1b was followed but using 22.0 g. of powdered iron, 1 ml. of concentrated hydrochloric acid, 400 ml. of dilute ethanol and 24.0 g. of 3-(1-piperidyl)propyl 4-nitro-2-n-propoxythiobenzoate, there was obtained about 22 g. of 3-(1-piperidyl)propyl 4-amino-2-n-propoxythiobenzoate. This thiol ester, in the form of its dihydrochloride salt, melted at 170.4-172.0° C. (cor.) with decomposition.

Anal.—Calcd. for $C_{18}H_{28}N_2O_2S \cdot 2HCl$: N, 6.84; S, 7.83. Found: N, 6.61; S, 7.77.

(b) 3-(1-piperidyl)propyl 4-n-butylamino-2-n-propoxythiobenzoate

When the procedure described above for Example 2b is followed but using 3-(1-piperidyl)-propyl 4-amino-2-n-propoxythiobenzoate in place of 3-diethylaminopropyl 4-amino-2-methoxythiobenzoate, there is obtained 3-(1-piperidyl)propyl 4-n-butylamino-2-n-propoxythiobenzoate.

13

EXAMPLE 13

(a) 3-(1-piperidyl) propyl 4-amino-2-n-butoxythiobenzoate

This preparation was carried out according to the procedure described above for Example 1b but using 18.5 g. of powdered iron, 1 ml. of concentrated hydrochloric acid, 400 ml. of dilute ethanol and 21.0 g. of 3-(1-piperidyl)-propyl 4-nitro-2-n-butoxythiobenzoate. There was thus obtained a quantitative yield of 3-(1-piperidyl)-propyl 4-amino-2-n-butoxythiobenzoate, which in the form of its monohydrochloride salt, melted at 155.0-157.0° C. (cor.).

Anal.—Calcd. for $C_{19}H_{30}N_2O_2S \cdot HCl$: C, 58.97; H, 8.07; Cl, 9.16. Found: C, 58.84; H, 8.10; Cl, 9.35.

(b) 3-(1-piperidyl) propyl 4-n-butylamino-2-n-butoxythiobenzoate

When the procedure described above for Example 2b is followed but using 3-(1-piperidyl)-propyl 4-amino-2-n-butoxythiobenzoate in place of 3-diethylaminopropyl 4-amino-2-methoxythiobenzoate, there is obtained 3-(1-piperidyl)-propyl 4-n-butylamino-2-n-butoxythiobenzoate.

EXAMPLE 14

(a) 2-diethylaminoethyl 4-amino-2-n-hexoxythiobenzoate

This preparation was carried out according to the procedure described above for Example 1b but using 12.8 g. of powdered iron, 1 ml. of concentrated hydrochloric acid, 400 ml. of dilute ethanol and 16.0 g. of 2-diethylaminoethyl 4-nitro-2-n-hexoxythiobenzoate hydrochloride. There was thus obtained a quantitative yield of 2-diethylaminoethyl 4-amino-2-n-hexoxythiobenzoate, which in the form of its monohydrochloride salt melted at 110.2-111.6° C. (cor.).

Anal.—Calcd. for $C_{19}H_{32}N_2O_2S \cdot HCl$: N, 7.20; Cl, 9.11. Found: N, 7.02; Cl, 9.28.

(b) 2-diethylaminoethyl 4-n-propylamino-2-n-hexoxythiobenzoate

Following the procedure described above for Example 2b but using 2-diethylaminoethyl 4-amino-2-n-hexoxythiobenzoate and propionaldehyde (1-propanal) in place of 3-diethylaminopropyl 4-amino-2-methoxythiobenzoate and n-butyraldehyde, respectively, there is obtained 2-diethylaminoethyl 4-n-propylamino-2-n-hexoxythiobenzoate.

EXAMPLE 15

(a) 2-diethylaminoethyl 4-amino-2-isobutoxythiobenzoate

When the procedure described above for Example 1b was followed but using 16.3 g. of powdered iron, 1 ml. of concentrated hydrochloric acid, 400 ml. of dilute ethanol and 19.0 g. of 2-diethylaminoethyl 4-nitro-2-isobutoxythiobenzoate hydrochloride, there was obtained a quantitative yield of 2-diethylaminoethyl 4-amino-2-isobutoxythiobenzoate, which in the form of its monohydrochloride salt melted at 163.0-164.2° C. (cor.).

Anal.—Calcd. for $C_{17}H_{28}N_2O_2S \cdot HCl$: N, 7.76; Cl, 9.82. Found: N, 7.66; Cl, 9.61.

(b) 2-diethylaminoethyl 4-n-butylamino-2-isobutoxythiobenzoate

Following the procedure described above for Example 2b but using 2-diethylamino-4-amino-2-isobutoxythiobenzoate in place of 3-diethyl-

14

aminopropyl 4-amino-2-methoxythiobenzoate, there is obtained 2-diethylaminoethyl 4-n-butylamino-2-isobutoxythiobenzoate.

EXAMPLE 16

2-diethylaminoethyl 4-(5-hydroxyamylamino)-2-methoxythiobenzoate

This preparation was carried out according to the procedure described above for Example 1c but using 13.0 g. of 2-diethylaminoethyl 4-amino-2-methoxythiobenzoate, 4.1 g. of zinc dust, 11.4 g. of glacial acetic acid, 200 ml. of dry benzene and 5.70 g. of 5-hydroxy-1-pentanal in 25 ml. of dry benzene. There was thus obtained 2-diethylaminoethyl 4-(5-hydroxyamylamino)-2-methoxythiobenzoate, which, in the form of its dihydrochloride addition salt, melts at 140.0-141.0° C. (cor.).

Anal.—Calcd. for $C_{19}H_{32}N_2O_3S \cdot 2HCl$: Cl, 16.08; S, 7.25. Found: Cl, 16.19; S, 7.29.

Other tertiary-aminoalkyl 4-(hydroxyalkylamino)-2-alkoxythiobenzoates which can be prepared according to the foregoing procedure using the appropriate tertiary-aminoalkyl 4-amino-2-alkoxythiobenzoate and hydroxyalkanal in place of 2-diethylaminoethyl 4-amino-2-methoxythiobenzoate and 5-hydroxy-1-pentanal, respectively, include the following: 2-diethylaminoethyl 4-(6-hydroxyhexylamino)-2-ethoxythiobenzoate; 3-(1-pyrrolidyl)propyl 4-(5-hydroxyamylamino)-2-n-propoxythiobenzoate; 2-(2,5-dimethyl-1-pyrrolidyl)-ethyl 4-(3-hydroxypropyl)-2-n-hexoxythiobenzoate; 2-(3-ethyl-1-piperidyl)-ethyl 4-(3-hydroxy-1-butylamino)-2-isobutoxythiobenzoate; and 2-(4-morpholinyl)ethyl 4-(4-hydroxybutylamino)-2-n-amoxythiobenzoate.

We claim:

1. A tertiary-aminoalkyl 4-substituted-amino-2-alkoxythiobenzoate having the formula

where X is a lower alkylene radical having from two to four carbon atoms whose two free valence bonds are on different carbon atoms, NRR1 is a member selected from the group consisting of lower dialkylamino, 1-piperidyl, (lower alkylated)-1-piperidyl, 1-pyrrolidyl, (lower alkylated)-1-pyrrolidyl and 4-morpholinyl, R2 is a lower alkyl radical having from one to six carbon atoms and R3 is a member of the group consisting of lower alkyl radicals having from one to six carbon atoms and lower hydroxyalkyl radicals having from two to six carbon atoms.

2. A dialkylaminoalkyl 4-alkylamino-2-alkoxythiobenzoate having the formula

where X is a lower alkylene radical having from two to four carbon atoms whose two free valence bonds are on different carbon atoms, and R2 and R3 are each lower alkyl radicals having from one to six carbon atoms.

15

3. A tertiary - aminoalkyl 4-alkylamino-2-alkoxythiobenzoate having the formula

5

10

where X is a lower alkylene radical having from two to four carbon atoms whose two free valence bonds are on different carbon atoms, NRR1 is a 1-piperidyl radical, and R2 and R3 are each a lower alkyl radical having from one to six carbon atoms.

4. A dialkylaminoalkyl 4-n-butylamino-2-alkoxythiobenzoate having the formula

20

25

where X is a lower alkylene radical having from two to four carbon atoms whose two free valence bonds are on different carbon atoms and R2 is a lower alkyl radical having from one to six carbon atoms.

5. A tertiary-aminoalkyl 4 - n - butylamino-2-alkoxythiobenzoate having the formula

35

40

where X is a lower alkylene radical having from two to four carbon atoms whose two free valence bonds are on different carbon atoms, NRR1 is a 1-piperidyl radical and R2 is a lower alkyl radical having from one to six carbon atoms.

6. 2-diethylaminoethyl 4 - n - butylamino-2-n-propoxythiobenzoate.

7. 3-(1-piperidyl)propyl 4 - n - butylamino-2-methoxythiobenzoate.

8. A process for the preparation of a tertiary-aminoalkyl 4 - substituted-amino-2-alkoxythiobenzoate having the formula

55

60

where X is a lower alkylene radical having from two to four carbon atoms whose two free valence bonds are on different carbon atoms, NRR1 is a member selected from the group consisting of lower dialkylamino, 1-piperidyl, (lower alkylated)-1-piperidyl, 1-pyrrolidyl, (lower alkylated)-1-pyrrolidyl and 4-morpholinyl, R2 is a lower alkyl radical having from one to six carbon atoms and R3 is a radical having from three to six carbon atoms selected from the group consisting of lower alkyl and lower hydroxyalkyl

65

70

75

radicals, which comprises treating a compound having the formula

with a reducing agent in the presence of a compound selected from the group consisting of an alkanal and a hydroxyalcanal each having from three to six carbon atoms.

9. A process for the preparation of a dialkylaminoalkyl 4 - alkylamino-2-alkoxythiobenzoate having the formula

20

25

where X is a lower alkylene radical having from two to four carbon atoms whose two free valence bonds are on different carbon atoms, R2 is a lower alkyl radical having from one to six carbon atoms and R3 is a lower alkyl radical having from three to six carbon atoms, which comprises treating a compound of the formula

35

40

with a reducing agent in the presence of an alkanal having three to six carbon atoms.

10. A process for the preparation of a tertiary-aminoalkyl 4 - alkylamino-2-alkoxythiobenzoate having the formula

50

55

60

where X is a lower alkylene radical having from two to four carbon atoms whose two free valence bonds are on different carbon atoms, NRR1 is a 1-piperidyl radical, R2 is a lower alkyl radical having from one to six carbon atoms and R3 is a lower alkyl radical having from three to six carbon atoms, which comprises treating a compound of the formula

65

70

75

with a reducing agent in the presence of an alkanal having three to six carbon atoms.

11. A process for the preparation of a dialkyl-

17

aminoalkyl 4 - n - butylamino-2-alkoxythiolbenzoate having the formula

where X is a lower alkylene radical having from two to four carbon atoms whose two free valence bonds are on different carbon atoms and R₂ is a lower alkyl radical having from one to six carbon atoms, which comprises treating a compound of the formula

with a reducing agent in the presence of n-butyraldehyde.

12. A process for the preparation of a tertiary aminoalkyl 4 - n - butylamino-2-alkoxythiolbenzoate having the formula

where X is a lower alkylene radical having from two to four carbon atoms whose two free valence bonds are on different carbon atoms, NRR₁ is a 1-piperidyl radical and R₂ is a lower alkyl radical having from one to six carbon atoms, which comprises treating a compound of the formula

with a reducing agent in the presence of n-butyraldehyde.

13. A process for the preparation of 2-diethyl-

18

aminoethyl 4 - n - butylamino-2-n-propoxythiolbenzoate which comprises treating 2-diethylaminoethyl 4 - amino - 2-n-propoxythiolbenzoate with a reducing agent in the presence of n-butyraldehyde.

14. A process for the preparation of 3-(1-piperidyl)propyl 4 - n - butylamino - 2-methoxythiolbenzoate which comprises treating 3-(1-piperidyl)propyl 4 - amino - 2-methoxythiolbenzoate with a reducing agent in the presence of n-butyraldehyde.
15. 2 - diethylaminoethyl 4 - n - amylamino - 2-methoxythiolbenzoate.
16. 3 - diethylaminopropyl 4 - n - butylamino-2-methoxythiolbenzoate.
17. 4 - diethylaminobutyl 4 - n - butylamino-2-methoxythiolbenzoate.
18. A process for the preparation of 2-diethylaminoethyl 4-n-amylamino-2-methoxythiolbenzoate which comprises treating 2-diethylaminoethyl 4-amino-2-methoxythiolbenzoate with a reducing agent in the presence of n-valeraldehyde.
19. A process for the preparation of 3-diethylaminopropyl 4 - n - butylamino-2-methoxythiolbenzoate which comprises treating 3-diethylaminopropyl 4 - amino - 2-methoxythiolbenzoate with a reducing agent in the presence of n-butyraldehyde.
20. A process for the preparation of 4-diethylaminobutyl 4-n-butylamino-2-methoxythiolbenzoate which comprises treating 4-diethylaminobutyl 4-amino-2-methoxythiolbenzoate with a reducing agent in the presence of n-butyraldehyde.
